(57) **CLAIM**

The ornamental design for a gaming controller, as shown and described.

DESCRIPTION

FIG. 1 is a top perspective view of the gaming controller showing the new design;

FIG. 2 is a top plan view thereof;

FIG. 3 is a bottom plan view thereof;

FIG. 4 is a left elevation view thereof;

FIG. 5 is a right elevation view thereof;

FIG. 6 is a front elevation view thereof;

FIG. 7 is a rear elevation view thereof;

FIG. 8 is a top perspective view thereof; showing the panel separately for complete disclosure;

FIG. 9 is a top plan view thereof;

FIG. 10 is a bottom plan view thereof;

FIG. 11 is a left elevation view thereof;

FIG. 12 is a right view thereof;

FIG. 13 is a front elevation view thereof;

FIG. 14 is a rear elevation view thereof;

FIG. 15 is a top perspective view of the large knob, show separately for complete disclosure;

FIG. 16 is a top plan view thereof;

FIG. 17 is a bottom plan view thereof;

FIG. 18 is a right elevation view thereof;

FIG. 19 is a left elevation view thereof;

FIG. 20 is a front elevation view thereof;

FIG. 21 is a rear elevation view thereof;

FIG. 22 is a cross-sectional view taken along the 22-22 line of FIG. 16;

FIG. 23 is a top perspective view of the small knob, shown separately for complete disclosure;

FIG. 24 is a top plan view of thereof;

FIG. 25 is a bottom plan view thereof;

FIG. 26 is a right elevation view thereof;

FIG. 27 is a left elevation view thereof;

FIG. 28 is a front elevation view thereof;

FIG. 29 is a rear elevation view thereof; and,

FIG. 30 is a cross-sectional elevation view taken along the 24-24 line of FIG. 24.

The broken lines in the drawings depict portions of the gaming controller that form no part of the claimed design.

1 Claim, 22 Drawing Sheets
